UNITED STATES PATENT OFFICE

2,248,875

KNITTING MACHINE

Alfred L. Hutton, Jr., Lonsdale, and Eugene St. Pierre, Pawtucket, R. I., assignors to Hemphill Company, Central Falls, R. I., a corporation of Massachusetts

Application December 5, 1938, Serial No. 243,914

7 Claims. (Cl. 66—135)

This case concerns a knitting machine for knitting fabrics wherein elastic yarn is incorporated with so-called plain yarn, for example, as in hosiery tops, and further, for incorporating patterns such as wrap stripe designs in such fabrics.

In the figures of drawings:

Fig. 1 is an elevation showing parts of the machine in which the invention is illustrated as seen from the front;

Fig. 2 is a plan of the latch ring, yarn feeding means, binder and cutter and control therefor;

Fig. 3 is an elevation taken at the left side of the machine showing the relative arrangement of the cylinder, sinker head and cap, latch ring, and controlling means for the binders and cutters and elastic yarn feeding means;

Fig. 4 is an elevation taken at the lower, left hand side of the machine in which the cams at the main cam drum and other controlling means are illustrated;

Fig. 5 is a section taken through the selecting drum and at the selecting plungers which function on instrumentalities which determine the wrap stripe or other pattern;

Fig. 6 is a section taken through the needle cylinder and showing the relative position and arrangement of the selecting means and needle dividing mechanism;

Fig. 7 is a section showing a fragment of the needle cylinder, a needle and a needle selecting jack;

Fig. 8 is a section showing the auxiliary stitch cam and controlling means along with the instep cam bracket, top instep cam and means for controlling the same;

Fig. 9 is an elevation showing a part of the machine including the instep cam bracket, part of the control for the instep cams, the auxiliary stitch cam and attendant mechanism;

Fig. 10 is a view showing the mechanism of Fig. 9 as seen from the left hand side of that figure, especially showing the interconnected control between the auxiliary stitch cam and a sinker cam at the auxiliary side;

Fig. 11 is an elevation showing parts of the machine adjacent and including the needle dividing cam and its controlling means;

Fig. 12 is a section showing the elastic yarn feeding means at the auxiliary side, the auxiliary binder and cutter and the manner in which yarn is introduced to the needles;

Fig. 13 is a view similar to that in Fig. 12, except that the parts are seen from the inside of the machine;

Fig. 14 is a section showing part of the elastic yarn feeding finger and binder and cutter therefor, the elastic feeding finger being in lowermost position;

5 Figs. 15 and 16 are detailed views showing opposite sides of the binder and cutter for the elastic yarn;

Fig. 17 is a plan of the sinker cap, a few sinkers and sinker butts being illustrated to show 10 the pathway, part of the cap being cut away to illustrate the cams which act upon the sinker butts;

Fig. 18 is a detail view showing the auxiliary sinker cam and part of its controlling mechanism;

Fig. 19 is a diagrammatic view of cams and 15 selecting elements showing the pathway of needle butts, jack butts and needle hooks during knitting in a typical stocking top in which the elastic yarn is to be incorporated and wherein wrap threads are knitted to produce a wrap pattern;

Figs. 20—22 respectively, show the cam arrangement on main pattern drums for controlling the elastic yarn feeding means, the dividing cam and the elastic or auxiliary binder and cutter; and

Fig. 23 is a view showing a sock in which a 20 top has been knitted as on the machine herein described.

In United States Patent #2,131,720 a knitted stocking top and method of knitting the same were disclosed wherein two yarn feeds, a main feed and an auxiliary feeding station were employed; a so-called plain yarn or yarns being knitted at the main feed and preferably upon all the needles while at the auxiliary feed, an elastic yarn was to be knitted on alternate needles only. A wrap stripe pattern may or may not be knitted, but if knitted, will be incorporated preferably by mechanism such as described in United States Patent #1,702,608, although other wrapping means may advantageously be employed. In the production of such a stocking top, the elastic is knitted under a suitable tension such as might be termed an ordinary knitting tension. It is not contemplated to knit under extreme tension as contraction of the fabric to produce a desirable rib appearance is forthcoming with very slight tension on the said elastic yarn. The elastic thus taken on every other or alternate needles and immediately knitted floats behind the intervening needles and the resulting fabric will have small loops of elastic alternating with plain knitted stitches in

35 40 45 50 55

the alternate wales, while the intervening wales will have loops of the so-called plain yarn only. The fabric and general method need not further be described here since a full description is available in United States Patent #2,131,720.

Referring to the figures of drawings, the invention is described as applied to a hosiery machine of the Banner type, although it is to be understood that the same applies to other machines such as so-called body machines, or to other types of hosiery machines. In Fig. 1 the principal parts of such a machine are illustrated in which a frame is generally indicated at 1, a circular base at 2, needle cylinder at 3 and a latch ring at 4. The needle cylinder carries the usual sinker head 5 and a sinker cap 6 specially constructed as will hereinafter be described more fully. A main cam shaft 7 carries drums 8 and 9 on which several cams for controlling the various parts of the machine are arranged. Only those cams which are particularly concerned in carrying out the present invention have been shown. Referring to Fig. 2, several main yarn feeding fingers are illustrated at 10.

The usual binder plate is illustrated at 11 having a main binder generally indicated at 12 and cutter at 13. The main binder is controlled by the usual lever 14 and link 15, the lever being pivoted at 16 on a bracket 17 attached to the upper face of the latch ring. This bracket also supports a spindle 18 having an extending finger 19 which operates the cutter 13. At the other end of that spindle is fixed a lever 20 which engages one of the fingers 10 for a purpose not necessary to describe in this case. The main binder and cutter are conventional in construction and function only upon yarns fed by the levers 10 so that their construction and operation need not be described in detail. The mechanism involves wrap striping means such as have been described in United States Patent #1,702,608 and certain parts which function in cooperation with said wrap striping means are evident in this Fig. 2. These parts include a bracket 21 by means of which a curved hook or finger 22 is supported, this hook being of common construction and usage in Banner wrap striping machines. It serves to hold the wrap threads in a position to be taken by selected needles and keeps said threads from non-selected needles. Other elements are the plate 23 and extending finger 24 which in cooperation with the plate 11 and hook 22 provide an opening through which wrap threads pass when floating.

Jack selecting means

Now referring to Figs. 5, 6, 7 and 19, those elements which serve to select needles for the wrap striping threads are shown. While it is not essential that the invention be practiced with wrap striping, one preferred form of the same does include such ornamentation and the complete disclosure of this case includes mechanism for performing that function which may or may not be employed at all times. The cylinder 3 has conventional latch needles 25 in the usual slots therein having butts 26. The arrangement of butts is according to the usual long and short butt groups, preferably about half the needles having long butts and the other half short butts. Under each needle is provided a jack 27 having a plurality of removable selecting butts 28 herein shown as seven in number. It must be understood that provision for seven butts or seven steps of selection is merely convenient in the particular instance and that more or fewer butts may serve to

effect the knitting of pattern work in accordance with the desires for more or less complicated patterns. Those jacks under short butt needles, those at the sole side of the machine, have a short butt 29 which is engaged by a cam later to be described for knitting a plain sole. A longer butt 30 is provided on alternate jacks, this butt being engaged by the so-called needle dividing cam to raise alternate needles for taking the elastic yarn. A master butt 31 on each jack serves further to control jacks for needles where some selection has been imparted through the butts 28.

A plurality of plungers 32 are arranged in supports 33 and 34 projecting upwardly from an element 35 supported on base 2. These plungers are arranged to slide more or less radially on the machine so as to engage butts 28 if in inward position, or to be drawn outwardly by springs 37 to a position in which they will not engage said butts. Each plunger has an extension 38 to which one of the springs 37 is attached, the other ends of said springs being attached to hooks 39 on an angular bracket 40. A drum 41 is supported for rotation on a spindle 42 being frictionally retained on that spindle by a friction element generally indicated at 43. Said drum is herein illustrated as having a plurality of discs 44 having butts 45 which are removable as by breaking or by any other suitable method. There are at least as many discs as plungers, but in this instance a dual set of discs has been illustrated and the purpose is to provide one set for knitting a pattern in the top and another for knitting a different pattern at some other part of the stocking. The spindle 42 is controlled by certain cam control at the main cam drum to change position of these discs so as to render effective either one group of them or the other. This particular mechanism is not essential for a single group of discs which effect patterning in the top of a stocking or that part of a fabric in which both a wrap pattern and elastic are to be incorporated. Thus a full description of moving spindle 42 and other essential characteristics of the change are not described at that time, but a full description will be found in copending application Serial #87,920, filed June 29, 1936.

A drum 41 is provided with a ratchet wheel having teeth 46, Figs. 1 and 5. A plate 47 is pivoted to be oscillated about the spindle 42 as a center and carries pawls 48 by means of which the drum is advanced step by step to present the butts 45 to actuate plungers 32. If a butt contacts the end of one of said plungers it is pushed inwardly so that its inner beveled end will engage such butts 28 as pass at its level. The plate 47 is oscillated to and fro by a link 49, bell crank lever 50 and other mechanism which derives its movement from some continuously rotating part of the machine. There is the usual mechanism for discontinuing the ratcheting of this drum at desired times and for retiming the same at the start of each new stocking or other knitted article.

At said desired times as in the sole of a stocking, patterning at that area may be undesirable and discontinued while the pattern is still knitted at the opposite or instep side. To accomplish this a cam 51, Figs. 5 and 6, known as the plain sole cam is also slidable within the guiding members 33 and 34 and tends to be held inwardly by a spring 52. This cam 51 engages upon butts 29 which, as before stated, are present on those jacks under needles which knit at the sole side of the machine. This cam is

held outwardly by a lever 53 pivoted at 54 and engageable by its hooked end 55 with an extension 56 which projects out from the stem of the cam. This lever 53 is controlled by a link 57 which is connectable to other elements moved at desired times from appropriate cams on one of the cam drums on the main cam shaft.

Needle and jack cams

Referring to Figs. 6, 8, 9, 10, 11 and 19, a detailed description of the various needle and jack cams will be given. At the main side of the machine is located the usual main cam block having stitch cams 58 and 59, center cam 60 and center raise cam 61. These cams are more or less conventional and need not be described in greater detail. Following this main cam group is a raise cam 62 which extends about the back of the machine and serves to raise needles which have knitted beneath stitch cam 59, but not to raise them high enough so that their latches will be cleared. Cam 62 has an extension 62'. All of the needle cams and some of the jack cams, or their supporting elements, are attached to cam plates 63, 64, Fig. 19.

At the auxiliary side, a cam 65 serves as a knitting cam and is movable radially of the machine by certain connecting elements. Referring to Figs. 8, 9 and 10, this cam 65 is attached to a stem 66 which is radially slideable within a bracket 67. The bracket 67 is in turn permanently connected to a larger bracket generally indicated at 68 and which is to be known as the instep cam bracket. A lug or extension 69 projects upwardly from the back of bracket 67 and has pivoted at 70 a bell crank lever 71. One arm of the bell crank lever extends downwardly to engage a projecting pin 72 at the outer end of the cam stem 66. This bell crank lever connects by means of its horizontal arm 73 which extends downwardly to mechanism for actuating the same and which will be described more fully in a later paragraph. This bell crank lever 71 also has attached thereto an angular projecting arm 74 which has a portion thereof indicated at 75 extending a considerable distance about the circumference of the sinker cap 6 and being concentric therewith. This concentric extension 75 serves to actuate a sinker cam, later to be described, in synchronism with movements of stitch cam 65. A spring 76, Fig. 8, normally tends to maintain cam 65 inwardly against the needle cylinder. In advance of this stitch cam 65 and beneath the cam plate 63 is located the needle dividing cam 77 shown in detail in Figs. 6 and 11. This cam 77 has an outwardly projecting stem 78 which is guided within a bracket 79 which attaches to the circular base of the machine. This bracket also has a lug 80 in which is pivoted a short spindle carrying a downwardly extending arm 81 and a horizontal arm at the opposite end thereof designated by numeral 82. This downwardly projecting arm 81 engages a projecting lug 83 on the stem 78. An angular projecting part 84 at the end of the stem has threaded therein an adjustable stop screw 85 which may be set to limit the inward movement of this cam 77 so that it may properly engage those butts with which it is to contact, namely, the butts 30. A spring 86 keeps the cam inwardly in butt engaging position except at such times as it is drawn outwardly by the levers 81, 82, link 87 and other mechanism for imparting movement to said link at the desired intervals.

That latter mechanism will be described in another paragraph of the description.

The top instep cam 88 is shown in Figs. 8 and 19 and is connected to a stem or post 89 which is movable vertically in the bracket 68. This instep cam is supplemented by a second instep cam (not shown in detail) for raising needles and movable radially to a position in which it will engage long butt needles. The cam 10 88 engages those same needles to draw them downwardly after completion of a heel or toe. In addition to its function as an instep cam, the cam 88 has a downwardly projecting portion 89 adjacent the stitch cam 58 which assures that needles which were raised for taking wrap threads are brought down to a position where they will engage cam 60 to be lowered prior to knitting under cam 59. Of course, when cam 88 is elevated as in knitting a heel or toe, no needles are being raised for taking wrap yarns. The instep cams are moved by a bell crank lever 90 pivoted upon a part of the bracket 68 and attached by a link 91 to the movable post 89. The radially movable cam (not shown) 15 is controlled by an inclined cam element 92 which is in turn attached to the movable post so that when the instep cam 88 is moved down, the cooperating, radially movable cam will be withdrawn and vice versa. This construction has 20 been described and claimed in copending application Serial #225,374 and will not be described more fully here. The movement for the instep cams is derived from the clutch shifter movement.

To this point, the cams described include the movable cams and raise cams 62 and 62'. There are certain other stationary cams which include the cam 93 which serves to raise needles after they have been drawn down below stitch cam 65 and two other cams 94 and 95, Fig. 19, outlined by dotted lines. These cams act upon the master butts 31, the lower cam 95 serving to raise jacks to level them for properly engaging selecting plungers 32 while the upper cam 94 serves 40 to manipulate jacks during reciprocatory work. Cam 96 also engages master butts 31 to raise jacks after they have been selected by plungers 32. If a jack is not selected by one of the plungers, the master butt 31 will pass beneath this cam 96 while such jacks as are selected will have their butts 31 necessarily contacting cam 96 which will raise the said jacks and their needles so that they will engage the wrap yarns 45 as will more thoroughly be described.

The cam 97 then serves to bring these jacks downwardly to more or less their lowest position after they have performed the selecting functions. The ends of cams 97 and 62 are properly shaped to function upon jacks passing in 50 either direction. No interference is experienced.

Elastic yarn feeding means

Referring to Figs. 2, 3, 12, 13 and 14, an elastic yarn feeding guide on finger 98 is vertically slideable in a slot 99 within a bracket 100 which is attached to the latch ring 4, other unimportant elements so far as this case is concerned intervening. This elastic yarn feeding finger has a stud 101 projecting outwardly through a groove 102 in the bracket, this stud having a collar 103 and a projecting pin 104. The collar 103 serves to maintain the finger within the slot 99 and to allow it to be moved vertically to and from feeding position. The finger has two openings, 55 the lowermost at the extreme feeding end,

through which the elastic thread designated at 105 is threaded. This elastic thread is drawn through a suitable tension and from any convenient yarn package or supply of the same.

For controlling this elastic feeding means a lever 106 is pivoted at 107 on a twisted bracket 108 which is also attached to a part of the latch ring 4. This lever 106 has a slotted end which engages the pin 104. A spring 109 connects at the outer end of the lever and to a fixed part of the mechanism upon which the bracket 108 is attached and serves the purpose of pulling the outer end down so that normally the yarn feeding finger is urged in an upward or inactive position. To limit this upward movement a stop 110 is attached to plate 111 which serves the purpose of raising the wrap spindle whenever the latch ring is elevated as when transferring. Of course, it is not desired to transfer on this type of machine when knitting hosiery with an elastic top, but the latch ring is raised for other purposes not necessary to be explained at this time.

A link or bar 112 has a forked upper end 113 which engages the other end of lever 106. This link 112 is adjustable for length and is guided to be vertically movable in slots, and at its lower end, bears upon the cam drum 8 or certain cams thereon, the construction and purpose of which will be described more fully thereafter.

Auxiliary binder and cutter

Now referring to Figs. 2, 3, 13-16, the auxiliary binder and cutter which functions only upon the elastic yarn is illustrated. This binder and cutter is necessary since the machine is of double feed machine when the elastic is being fed and since it is desirable to withdraw that elastic yarn when the same is not being knitted into the fabric. The fact that the machine is a two feed machine and that the elastic is separately fed and controlled makes it possible to have the main binder and cutter entirely free of elastic for use of the plain yarns only. This allows the elastic binder construction to be suitable for that particular type of yarn and does not make it necessary to employ a special binder and cutter at the main side such as would accommodate both types of yarn and which, although the same may be made to function satisfactorily, are more complicated and a little harder to employ satisfactorily.

To the main binder plate 11 there is attached a stationary binder and cutter element having a connecting foot 114, a vertical post 115 and a yarn guiding notch 116 which is cut into the post and is terminated at the lower end in a sort of guiding hook 117. At either side of the vertical post which is slotted as shown at 118 are plates 119 and 120. The plates 119 and 120 are interconnected by a bolt 121 having an adjusting nut 122 between which and the plate 120 is a spring 123. The spring 123 is under sufficient tension to press the plates together so that they may cut and clamp the yarn more effectively. At the upper end of these plates 119 and 120 is a pin 124 which serves to maintain these movable parts of the binder and cutter working in proper vertical relationship along the slot 118. Said pin also serves to be engaged by the forked end of a lever 125 by means of which the binder and cutter is actuated.

The extension 117 beneath the notch 116 serves to guide the elastic yarn to a position where it will be cut and bound properly; also one side of

this element serves as a complementary shearing edge for the plate 119. The other plate 120 will bind the elastic yarn against the extending ledge 126. The plate 120 not only binds the elastic against that ledge but also squeezes it against the side of the hook 117 so that the elastic will be bound before it is cut although the plate 120 does not reach its full extent of travel to clamp against the ledge 126 until after the cutting has been completed.

The lever 125, Figs. 2 and 3, is also pivoted upon the stud or spindle 16 and has connected to its outer end a downwardly extending link or rod 127 which is connected to a lever later to be described and through which this binder and cutter are actuated from certain suitable cams on the drum 9.

Special sinker control

Now referring to Figs. 17 and 18, the sinker cap generally designated at 6 is shown cut away to illustrate the shape of the regular sinker cams 128 and 129 and the center sinker cam 130. Sinker butts 131 are illustrated taking the usual pathway at that main side of the machine. A few sinkers are shown as at 132 to illustrate at their inner ends by dot and dash lines 133, the actual pathway of the sinker wave.

At the opposite or auxiliary side two more cams 134 and 135 function during knitting of the elastic at that side to impart a wave to sinkers along with the movable center sinker cam 136. That sinker cam 136 is connected to a slide or stem 137 which is radially movable within a suitable slot beneath a plate 138 in the sinker cap. The said cam is illustrated in active position in Fig. 17, but is projected inwardly to inactive position in Fig. 18. A spring 139 engages pin 140 and normally tends to hold this cam in active position as in Fig. 17. Referring back to Figs. 8, 9 and 10, the extensions 74, 75 were described briefly at that time and it is that concentric part 75 which bears against the outer end of the slide or stem 137. When elastic is being knitted cam 65 is allowed to move in for engagement with needle butts to impart to them a stitch wave at that point and at the same time, cam 136 will be allowed to move outwardly satisfactorily to control the sinkers. As the cam 65 is withdrawn at the end of elastic knitting, the end 136 will be pushed in against the tension of spring 139 and the sinker wave at that side of the machine will be terminated so that sinkers will hold the fabric down on the needles all about the machine except at the main feed.

Main cam drum set-up

Referring to Figs. 1, 4, 20, 21 and 22, the main cam shaft has been generally indicated by numeral 7 and two drums 8 and 9 thereon have been shown. Certain cams on these drums control the various cams and other functioning parts heretofore described. Beginning at the right in Fig. 1, the first link or bar is that which controls the elastic yarn feeding finger and which is shown at 112 in Fig. 3. That link projects downwardly and is engaged by a cam designated at 141, Figs. 1 and 20. This cam has two high points or lobes at 142 and 143. These lobes are for the purpose of lifting the outer end of lever 106 a little higher and incidentally moving the feeding finger 98 down a little farther than is necessary when the elastic thread is being taken continuously at the needles. The lobe 142 functions when yarn is first introduced. At the

ordinary feeding position the angle at which the yarn is held between the finger 98 and the binder 120 is such that the yarn is not taken with too great certainty. The regular feeding position is shown in Fig. 12 while Fig. 14 illustrates the position the guide 98 assumes when either the lobes 142 or 143 are functioning upon link 112. The additional movement is only imparted when introducing the elastic yarn and when withdrawing the same. Between these points it will be taken satisfactorily once it has been engaged by several needles. The reason for feeding in the higher position is that the higher position is more satisfactory because the guide 98 which functions pretty close to needle hooks will be out of the way and not likely to smash against the needle hooks. The second lobe acts when the last few elastic stitches are to be knitted. At that time the dividing cam 77 starts to be withdrawn and if a few needles did not rise to a complete height, the temporary lowering of guide 98 at that movement would assure that these needles would take their yarn.

The next link and the only other one of this group being controlled from drum 8 is the link 87, Figs. 1, 6 and 11, which is controlled by a cam 144 on the drum 8, Figs. 1 and 21. This cam lifts the link 87 and withdraws the needle dividing cam 77 at all times except when the elastic yarn is to be fed. At that time the link will drop from the cam 144 and will remain in the depression as illustrated at the top of Fig. 21 until the elastic top has been completed and at which time the guiding cam will be withdrawn.

The link 73, Figs. 4, 8 and 10, extends downward from the lever 71 by means of which it controls the auxiliary stitch cam 65 and auxiliary sinker cam 136 and connects at its lower end to an extension 145 projecting up from the arm 146 which is pivoted to the stud 147 at that side of the frame. This arm 146 has a cam engaging toe 148 by means of which it is controlled by a cam 149 on drum 9. The cam maintains the stitch cam 65 outwardly and pushes the sinker cam 136 inwardly except at such times as the elastic top is being knitted. It will be noted that the cam 149 is substantially of the same extent and the depression therein is at substantially the same relative circumferential position so that cams 65, 136 and 77 function practically at the same time.

The main binder is actuated by a link 15, Figs. 2 and 5, which is in turn connected to a lever 150 which is controlled by certain suitable cams on the cam drum 9. The binder is also actuated in a known manner as the lever 151 which is contacted by lugs 152 on a drum 153 at the stiper shaft 154 at the back of the machine. The auxiliary or elastic yarn binder is actuated by connections leading down through link 127 to the outer end of a lever 155 also pivoted at 147, Figs. 4 and 22, and which is actuated by a cam 156 on the drum 9. This cam is so positioned and is of sufficient extent to open the elastic binder at a suitable interval before the elastic yarn is to be withdrawn, but is timed to close that binder at the proper moment as the said elastic yarn is withdrawn from the needles. The relative position and extent of said cam is shown in Figs. 4 and 22.

Operation

In Fig. 23 an anklet or sock is illustrated having a leg 157 and foot 158. The top generally indicated at 159 shows in a more or less conven-

tional manner the way in which the elastic is drawing spaced wales together to simulate a rib appearance and to contract the same so that the entire top has the general shape and fabric characteristics of a transferred rib top. A design has been made by wrapping certain areas 160 with a colored or otherwise contrasting yarn.

At the termination of knitting in a preceding article, the machine makes a move at which the completed article is to be cast off. At this same move the stitch cam 65, dividing cam 77 and a latch opener (not shown) are moved in active position. This prepares the machine for knitting at the auxiliary side as soon as the elastic yarn is dropped to feeding position. That occurs on the next move when the link 112 is raised up to the lobe 142 of the cam 141. That moves the elastic feeding finger 98 down to the position shown in Fig. 14 so that it is sure to be taken by the first divided or raised needle encountered. It is to be understood that alternate needles are being raised by cam 77 while intermediate needles do not rise high enough to take the elastic yarn. This elastic is taken by raised needles for two courses, but since the first course is cast from the needles as they pass the main yarn feed, that course of elastic is merely incidental and does not appear in the finished fabric. The reason for taking the elastic during two courses is that the machine provides a move or a change every two revolutions. Thus it is necessary after dropping in the elastic to knit it for two revolutions before the plain yarn may be dropped to feeding position.

On the next move the plain yarn drops to feeding position at the main side and will immediately start to knit. As it does so, it will lock the elastic yarn which was taken on every other needle, at this point both the elastic and plain yarn are feeding, the plain yarn to all needles and the elastic to alternate needles. Each yarn knits at its own station and both produce the fabric of United States Patent #2,131,720. If a wrap pattern is to be knitted in this section of fabric, the wrap mechanism and the pattern mechanism may be brought into position at any time after the initial course or selvage has been started. Presumably the wrapping will commence immediately after the start of the initial course or courses and will continue until practically the last course in the knitted top.

At the end of knitting in the top, one move which is a long move terminates knitting the elastic and also the pattern if the latter has not been removed from operative position previously. On this single move the dividing cam, stitch cam 65, latch opener and the elastic yarn feeding finger 98 are withdrawn from position; also the binder takes the elastic yarn and severs it. In actual operation these functions are timed to occur at slightly different intervals although all on the same move. The stitch cam is withdrawn first, then the dividing cam and then the yarn feeding finger at which time the binder receives the yarn and severs it. The latch opener may come out at any time after the elastic knitting has been completed. While these functions are timed to occur at slightly different intervals, the interval is extremely slight and merely sufficient to assure that each of these functions follows in the proper operative relationship.

On this last move the lobe 143 would control the elastic feeding finger to move the same downwardly slightly to assure that the elastic was taken by the last needle intended to knit it.

Referring to Fig. 19, the path of the various needle and jack butts has been shown. The butts 30 engage cam 77 and are raised up in a pathway 161 while the intermediate jacks will not be elevated since they have no butt corresponding to the butt 30. At this time the needles will be raised along with the jacks so that needle hooks take the pathway at 162 taking the elastic yarn 105 which is feeding from the finger 98. The other needles pass beneath the feeding finger and come up in front of the floats of elastic yarn extending between alternate needles, then all needles pass downwardly as their butts travel pathway 163 beneath cam 65. The said alternate needles knit the elastic yarn at that point. 15 Thereafter needles are raised by cam 93 to the usual height which they assume after knitting or when passing along their raise cams. The jacks are then raised by cam 95 which engages butts 31 until they are at the proper elevation to be engaged by selecting plungers 32. If certain ones are lifted by these plungers, they will then be further elevated by cam 96 which functions upon the master butts. Other jacks will merely pass along so that the master butts travel just below the point of said cam 96. Those that are selected cause their needles to be raised so that the butts travel in pathway 164 and the hooks to move in pathway 165 and to take wrap threads from a wrap thread carrier 166, a fragment of which is shown in this figure. The other needles pass along at the normal level and are raised up front stitch cam 58 so that their latches are cleared. Naturally the selected needles have their latches cleared when selected and are thereafter moved down by the point 89 of the cam 88 and join the pathway of the needles raised by cam 58 as they strike the cam 60. Here they take a plain yarn feeding through one of the yarn fingers 10 and knit as they pass down beneath cam 59. Thereafter they rise and are guided by cam 62.

The machine may be used without resort to the complete method which includes ornamentation by wrapping, in which case the base fabric of plain yarn and elastic only will be produced. As a further variation, the machine may be slightly modified by raising all needles to the path 162 so that they take the elastic, but knitting only on alternate needles. This may be accomplished by feeding at a lower position after the selavage course which must necessarily be knitted as hereinafter described. Since only the needles which rise to path 162 would have their latches cleared, the other needles would not knit off even though they pass beneath stitch cam 65. This means that they would tuck or accumulate a loop of plain or elastic yarn which would be knitted off on passing through the main yarn feed subsequently thereto. This method results in a fabric such as illustrated in copending application Serial #238,462, filed November 2, 1938. Other modifications and changes which would fall within the scope of the invention as originally conceived may be apparent to those skilled in the art and the invention is to be limited only by the scope of the appended claims.

We claim:

1. In a knitting machine, a vertically movable elastic yarn feeding finger, means for moving said finger vertically to and from a feeding position including cam means having effective cam surfaces at different heights whereby upon the introduction and withdrawal of said yarn, the finger will be moved to a lower level than during

continuous feeding between said two extreme points.

2. In a knitting machine a movable yarn feeding finger, means for moving said finger to and from a feeding position including cam means with effective surfaces at two different heights whereby on the initial movement to feeding position and upon withdrawal from feeding position, the finger will be caused to move to a lower feeding position with respect to needles than it occupies while feeding in the interim.

3. In a knitting machine, the combination of a vertically movable yarn feeding finger, a binder and cutter adjacent said finger and within the needle circle for holding a yarn threaded through said finger, means for moving said finger to an extreme feeding position, then for raising said finger slightly to feed above the hooks of passing needles and thereafter for returning the finger to the extreme position just before withdrawal of the yarn.

4. In a knitting machine the combination of means at two independent feeding stations including needles, yarn feeding means at one of the stations and needle actuating cams thereat for raising all needles to take the yarn and to draw it into knitted stitches, and means at the other of said stations for raised spaced needles only to take yarn fed thereat and draw it into knitted loops on said spaced needles, said means for feeding the yarn at said second station including a movable yarn feeding finger, a binder and cutter for the yarn operable at such times as the yarn is to be withdrawn from feeding, sinker controlling means including a center sinker cam and means under pattern control for simultaneously rendering the said needle and sinker controlling means active and inactive including a common operating member connected at one part to the needle controlling means and at another part to a sinker controlling means.

5. In a knitting machine the combination of means at two independent feeding stations including needles, yarn feeding means at one of the stations and needle actuating cam thereat for raising all needles to take the yarn and to draw it into knitted stitches, and means at the other of said stations for raising spaced needles only to take yarn fed thereat and draw it into knitted loops on said spaced needles, said means for feeding the yarn at said second station including a movable yarn feeding finger, means under pattern control for moving said finger to and from feeding position, a binder and cutter for the yarn operable at such times as the yarn is to be withdrawn from feeding, and sinker controlling means at that feeding station operable to impart to said sinkers a stitch wave when yarn is fed, but not to impart such wave when yarn is withdrawn from feeding position, said sinker control being simultaneously effected by mechanism including a bell crank lever connected at one end to means for actuating needles and at the other end to said sinker controlling means.

6. In a knitting machine the combination of means for feeding and knitting yarn at two feeding stations, means in advance of one of said feeding stations for selecting spaced needles only to raise them to take an elastic yarn and means thereat for causing said raised needles which have taken yarn to draw stitches, other means for controlling sinkers at said elastic yarn feeding station whereby a sinker wave will be imparted while the elastic yarn is being fed at that station, but otherwise sinkers will not be affected

when elastic yarn is not feeding, and means simultaneously operable upon said sinker controlling means and means for causing needles to draw stitches of said elastic yarn including a common lever connected at one end to stitch drawing means and at the other end to sinker controlling means and adapted upon rocking movement to impart the necessary movement to both for rendering them effective in producing needle and sinker movements or rendering both inactive.

7. In a knitting machine, the combination of a movable yarn feeding finger, a binder and cutter adjacent said finger and within the needle circle

for holding a yarn fed through said finger, means for moving said yarn feeding finger to and from a yarn feeding position and also to an extent so that the same passes through said feeding position and to a so-called extreme feeding position at which the said yarn is more effectively introduced to needles, cam means for controlling the movement of said yarn feeding finger having cams of two different heights, one for determining the said feeding position and another for determining said extreme position.
